UNITED STATES PATENT OFFICE

152,714

DESIGN FOR A COMBINED MOTOR VEHICLE GRILLE AND BUMPER

Edward Macauley, Grosse Pointe Farms, Mich.,
assignor to Packard Motor Car Company, Detroit, Mich., a corporation of Michigan

Application September 12, 1947, Serial No. 141,333

Term of patent 14 years

(Cl. D14—18)

To all whom it may concern:

Be it known that I, Edward Macauley, a citizen of the United States, residing at Grosse Pointe Farms, county of Wayne, State of Michigan, have invented a new, original, and ornamental Design for a Combined Motor Vehicle Grille and Bumper or Similar Article, of which the following is a specification, reference being had to the accompanying drawing, forming a part thereof.

Fig. 1 is a front elevational view of a combined motor vehicle grille and bumper embodying my new design.

Fig. 2 is a front perspective view looking from the left hand side.

The dotted line showing in the drawing is for illustrative purposes only.

I claim:

The ornamental design for a combined motor vehicle grille and bumper or similar article, substantially as shown and described.

EDWARD MACAULEY.
